No. 619,029.

Patented Feb. 7, 1899.

R. WALLACE.
CAR.

(Application filed May 27, 1898.)

(No Model.)

UNITED STATES PATENT OFFICE.

ROBERT WALLACE, OF MIDWAY, KENTUCKY, ASSIGNOR OF ONE-HALF TO
GEORGE H. DUNHAM, OF CINCINNATI, OHIO.

CAR.

SPECIFICATION forming part of Letters Patent No. 619,029, dated February 7, 1899.

Application filed May 27, 1898. Serial No. 681,939. (No model.)

To all whom it may concern:

Be it known that I, ROBERT WALLACE, of Midway, in the county of Woodford and State of Kentucky, have invented certain new and 5 useful Improvements in Cars; and I do hereby declare the following to be a full, clear, and exact description of the invention, such as will enable others skilled in the art to which it appertains to make and use the same.

10 My invention relates to an improvement in cars, and more particularly to coal-cars, the object of the invention being to provide a simple and efficient cover for a coal-car, whereby to protect the contents of the car from theft 15 and the weather, and which can be conveniently opened for the purpose of loading the car.

15 A further object is to provide a coal-car with a sectional cover and to construct locking means in such manner that all the sections at one side of the car can be secured with a single seal.

20 A further object is to provide a cover for a coal-car which shall be easy to manipulate 25 and which shall be effectual in all respects in the performance of its functions.

25 A further object is to produce a covered coal-car which can be easily loaded and unloaded.

30 With these objects in view the invention consists in certain novel features of construction and combinations and arrangements of parts, as hereinafter set forth, and pointed out in the claims.

35 In the accompanying drawings, Figure 1 is a view of a coal-car embodying my invention. Fig. 2 is a cross-section of the same. Fig. 3 illustrates a modification.

40 A represents the body of a coal-car, to the sides of which, preferably at the upper ends of the standards, rafters 1 are secured, said rafters extending from opposite sides of the car upwardly and toward each other and at their upper meeting ends are connected together by means of cross-bars or braces 2. The meeting ends of the rafters support a footboard 3, running the full length of the car, as in box-cars. The space under the rafters at the respective ends of the car is closed 45 by extending the ends of the car upwardly. 50

The several pairs of rafters are spaced apart any desired distance, and any desired number of such pairs of rafters may be employed. The top of the car is thus divided transversely (by the pairs of rafters) into several 55 sections, and each section is to be closed when the car is loaded by means of a door 4, said doors constituting a sectional roof for the car. Each door is hinged at its upper edge at one side of the footboard 3, so that when raised 60 or opened it may be turned over said footboard and be supported thereby. When the doors or roof-sections 4 are closed, they will be supported at their edges by means of the rafters, and the free edge of each door or roof-section may be provided with a staple 5 to receive a suitable loop or hook 6, projecting from a rod 7, mounted at the side of the car. Through all the staples 5 on the doors the projecting loop 6 of the rod 7 is passed, and 70 the end of each rod is provided with an arm 9, secured by means of a suitable seal 10. Thus all the doors or roof-sections can be locked by means of two seals, one at each side of the car, or, if desired, both rods 7 at the 75 respective sides of the car may be secured by means of a single seal.

In order to facilitate the unloading of the car, the latter may be provided in its side, preferably at or near one end, with a door 8, 80 normally locked by arm 9 and seal 10.

From the construction and arrangement of parts above set forth it will be observed that the car can be tightly closed and locked when loaded, and thus the contents will be safe 85 from theft and will be protected from the effects of the weather. The sections of the roof can be easily opened when unlocked, and the car can be loaded as easily as are coal-cars having no roof. 90

If desired, the doors or roof-sections may be made to slide, as shown in Fig. 3, instead of hinged, as above described.

My improvements are simple in construction, are comparatively inexpensive, and are 95 effectual in all respects in the performance of their functions.

Various slight changes might be made in the details of construction of my invention without departing from the spirit thereof or 100

limiting its scope, and hence I do not wish to limit myself to the precise details herein set forth.

If desired, the doors or roof-sections may 5 be so hinged that they may be rolled back, and they will preferably be made in sections hinged together, thus affording easier manipulation in opening and closing, as shown in Fig. 2.

10 Having fully described my invention, what I claim as new, and desire to secure by Letters Patent, is—

15 1. The combination with a car, of a series of doors closing the top thereof, and a staple or keeper on each door, of a common locking-bar mounted on the side of the car and having a series of engaging devices for the staples or keepers of the respective doors, substantially as set forth.

20 2. The combination with a car, a door in the side thereof and a series of doors adapted to cover the car, of a common locking-rod constructed to engage and lock the various top or cover doors and also the door in the 25 side of the car.

3. The combination with a car and rafters

secured to the sides thereof and connected together at their meeting ends, of doors hinged at their upper edges and adapted to rest on said rafters, a locking bar or rod extending 30 the full length of the car and having an engaging device for each door and a seal connected with each bar or rod and adapted to normally prevent the same from being turned, substantially as set forth. 35

4. The combination with a coal-car, of a door in the side thereof and a movable sectional cover for the car, a locking-rod having engaging devices for the respective sections of the cover, an arm projecting from said 40 locking-rod and adapted to receive a keeper on the door in the side of the car and a seal adapted to prevent disengagement of said arm, substantially as set forth.

In testimony whereof I have signed this 45 specification in the presence of two subscribing witnesses.

ROBERT WALLACE.
